J. R. STARK

BILLIARD CUE

Filed June 28, 1922

Inventor

J. R. Stark.

Lacey, Lacey, Attorneys

UNITED STATES PATENT OFFICE.

JOHN R. STARK, OF NASHVILLE, TENNESSEE, ASSIGNOR OF ONE-HALF TO HENRY C. MANSON, OF NASHVILLE, TENNESSEE.

BILLIARD CUE.

Application filed June 28, 1922. Serial No. 571,480.

To all whom it may concern:

Be it known that I, JOHN R. STARK, a citizen of the United States, residing at Nashville, in the county of Davidson and State of Tennessee, have invented certain new and useful Improvements in Billiard Cues, of which the following is a specification.

The present invention relates to improvements in billiard cues and has for its main object to provide a novel construction of the tip of the cue, whereby the tip is held on very securely without the use of glue, so that it cannot be torn off or become loose. This has the advantage, that the tip will last much longer than usual and it can be worn down to the last shred.

It often occurs in the middle of a game that the glued-on tip becomes loose or unattached and this may seriously affect the game, as a player generally has a favorite cue and it takes several hours to have a new tip attached thereon.

Another object of this invention resides in the fact, that a special housing is provided for the tip. The advantage of this will be readily understood, as the player may remove the tip and put it in his pocket after finishing the game. The cue will then be in good condition for his next game, as nobody can use it without the tip.

In the accompanying drawing one embodiment of the invention is illustrated; and

Figure 1 shows an elevation of a cue complete with the improved tip;

Figures 2 is a fragmentary elevation and longitudinal section of the end of the cue; and

Figure 3 shows in perspective view the detail parts of the improved attachment.

The cue 10 has the usual shape with a heavy butt end 11 and tapering down to a comparatively narrow tip end 12. At this end is secured a sleeve 13 which may be threaded a metallic rod screwed into the tip end 12 or fastened in any other suitable manner so that the outside of the sleeve 13 forms an uninterrupted continuation of the outer face of the end 12. At the forward end of this sleeve is formed a recess 14, which is preferably threaded. A tip 15, which is as usual made of some resilient material, is inserted in a housing 16. This

housing is preferably split along an axial plane 25 so as to form two mating parts 55 abutting along this plane and a shank 17 is formed on the inner end of the housing adapted to screw into the recess 14 in the sleeve 13, a shoulder 18 being formed at the base of the housing which, when the 60 housing is screwed into the sleeve 13, forms a tight joint between the housing and the sleeve as at 19. The housing 16 has a chamber 20 adapted to receive the tip 15 and in order to rigidly hold the tip in the 65 housing, pointed gripping teeth 21 are formed around the inner periphery of the chamber which will grip around the tip when inserted in the chamber. When thereupon the housing 16 is screwed into the 70 sleeve 13 the teeth 21 will become embedded in the tip in such a manner that it cannot become detached from the cue.

As best seen in Figure 3 the shape of the tip 15 is the same as that of tips ordinarily provided, so that it will require no special construction of the tip to be adapted for this construction of the cue.

It will now be understood that the tip with its housing, although removable from 80 the end of the cue, will not in any manner become loose or detached from the cue during its use. This is naturally a great advantage, as the game is often interfered with by loose tips during the play.

By simply unscrewing the housing 16 from its seat the cue cannot again be used until the tip is attached and in this manner the owner of the cue will have his assurance that the cue is in readiness for his 90 next game without having been tampered with in the meantime.

The sleeve 13 and the housing 16 are preferably made of some light material such as aluminum, so that no increased 95 weight at the end of the cue will occur from this construction.

Having thus described the invention, what is claimed as new is:

An attachment for billiard cues comprising a tip of resilient material, a housing for the tip, said housing being provided with a recess having teeth for gripping said tip, an exteriorly threaded shank on said housing, said housing being divided 100 along a central axial plane and provided 105

with a shoulder at the juncture between the shank and the body portion of said housing, a sleeve threaded on said shank and abutting against said shoulder, and a metallic rod securely fastened in the tip end of the cue and having threaded engagement with said sleeve, the exterior diameter of

said housing and said sleeve being identical with the tip end of the cue, thereby producing an uninterrupted surface of the connected parts. ¹⁰

In testimony whereof I affix my signature.

JOHN R. STARK. [L. S.]
